James J. Morissett, of New York, N.Y.
Assignor to
Jacob L. Dodge.
Whole No. 1486, Letters Patent No 121, dated Oct. 29, 1861.

The schedule referred to in these Letters Patent and making part of the same.

To all whom it may concern:

Be it known that I, James J. Morissett, of the City, County and State of New York, have invented a new Design for Hats; and I do hereby declare that the following is a full, clear and exact description of the same, reference being had to the accompanying drawing forming part of this specification, in which —

Figure 1. is a side view of a hat of my new design.

Figure 2. is a top view of the same.

Figure 3. is a central section of the same, from back to front.

Similar letters of reference indicate corresponding parts in the several Figures.

My design for hats consists in a novel configuration of the brim suitable for hats of felt, felt covered with plush, cloth, or other material, or for hats of any other fabric.

A. is the brim having a downward curvature from the sides toward the front and back as shown at a, a, b, in Figures 1 and 3 and turned up angularly all around as shown at c, c, c, in Figure 3, in such manner that at the front, back and sides of the hat it has an upright direction as shown at d, d, in Figure 3, and at two points on each side at equal distances or thereabouts from the front and back its edge is drawn in quite close to the crown as shown at e, e, e, e, in Figures 1 and 2, so that its (the edge) as viewed from the top presents four salient curves f, f, f, f and four recentering curves g, g, g, g as shown in the last mentioned Figure.

(What I claim as my design and desire to secure by Letters Patent, is -

The configuration of the brim of the hat as illustrated by the several Figures of the drawing and herein described.
